Attorney

UNITED STATES PATENT OFFICE.

DAVID LIPPY, OF MANSFIELD, OHIO.

MEAT-SAWING MACHINE.

SPECIFICATION forming part of Letters Patent No. 599,571, dated February 22, 1898.

Application filed January 11, 1897. Serial No. 618,853. (No model.)

To all whom it may concern:

Be it known that I, DAVID LIPPY, a citizen of the United States, residing at Mansfield, in the county of Richland and State of Ohio, have 5 invented certain new and useful Improvements in Meat-Sawing Machines; and I do declare the following to be a full, clear, and exact description of the invention, such as will enable others skilled in the art to which it 10 appertains to make and use the same, reference being had to the accompanying drawings, and to the letters and figures of reference marked thereon, which form a part of this specification.

15 My invention relates to improvements in meat-sawing machines; and the objects of my invention are, first, to provide a power-machine of the class known as swinging "circular saws," for slicing meat to be used in meat- 20 markets and for other purposes; second, to so arrange the swinging saw that it can be moved any required distance without changing its relative position to the platform; third, to make a cheap, durable, and efficient means 25 for the purpose stated. I attain these objects by the mechanism illustrated in the accompanying drawings.

This application is one of a series filed by me of even date herewith for improvements 30 in meat-sawing machines and bearing, respectively, the Serial Nos. 618,851 and 618,852.

Figure 1 is a side elevation of my improved 35 swinging circular saw and mode of operating the same, and also showing the frame in section for supporting the table carrying the separate adjustable platforms. Fig. 2 is a top plan view of the frame, showing the table provided with the separate platforms; and Fig. 3 is a front elevation of the swinging saw- 40 arm carrying the circular saw.

In the drawings, A indicates the frame of the machine; B, the table, on which are mounted the sliding platforms. C and D are brackets or hangers attached to the ceiling of the 45 room; E, a shaft journaled in the hangers; F and F', loose and tight pulleys mounted on the shaft. M is a grooved pulley also mounted on the shaft.

G is a swinging arm composed of two bars 50 H H', the said bars being connected at their lower ends, the upper ends being bent out-

wardly and then parallel with each other, and each is provided with an eye through which passes the shaft E. The swinging arm has attached to one of its sides, near the 55 lower end, a handle, and at its extreme lower end it is provided with the shaft Q, on which two laterally-extending arms P P' are journaled. A pulley R is also placed upon the said shaft between the vertical bars H² and 60 H³. There is also a pulley S placed upon a suitable shaft above the pulley R. A saw-mandrel T, pulley U, and circular saw V are journaled in the loose ends of the horizontal arms P. The said arms are also provided 65 with the downwardly-projecting bar W. The said bar is bifurcated at its lower end and provided with a grooved roller X to guide the saw and carry the same parallel with the top of the table Y. One belt Z conveys motion 70 to the circular saw from the counter-shaft E by the belt passing around the pulleys M and U and upon the under side of the tightener-pulleys R and S.

The top of the table A² is provided with 75 any number of grooves B², and in which are placed the adjustable platforms C². Each platform is provided with a roller D², the said rollers provided with pointed spikes E², and a meat-clamping device composed of a lever 80 having a vertical arm F² and horizontal arm G², also a vertical notched lever I². The said levers are hinged one upon each side of the platform and are for the purpose of holding the meat firmly in position when the saw is 85 in the act of cutting the same. A raised guide J² is secured upon the edge of the table in a line with the center of the swinging arm, and upon the same operates the roller X.

It will be readily seen by those skilled in 90 the art that when motion is conveyed to the counter-shaft E by any suitable motor power that motion is conveyed to the circular saw V by the belt connection Z. Each one of the adjustable platforms 1, 2, 3, and 4 can be 95 brought in line with the saw at the will of the operator and the others moved out of line, so that only one kind of meat is in line with the saw. The operator grasps the handle R², forcing the saw through the joint of meat to be 100 sliced. Different joints or kinds of meat can be placed upon the different platforms, obvi-

ating the necessity of removing the joints of meat if the customer should require a different kind.

Having fully described my invention, what I claim as new, and desire to secure by Letters Patent, is—

1. In a meat-sawing machine, the combination of a frame supporting a table carrying sliding platforms, each platform provided with a roller, a meat-clamping device located on each side of the sliding platform, a swinging arm comprising two bars joined together at their lower ends, a pulley journaled in said lower ends, the upper ends of the bars being journaled on the shaft supported by brackets extending from the ceiling, a loose and tight pulley and a grooved pulley also journaled on the shaft attached to the ceiling, a guide-pulley journaled between the bars of the swinging arm just above the pulley in the lower end thereof, a horizontal arm attached to the lower end of the swinging arm, and comprising two parallel bars in the outer free ends of which is mounted a shaft on which is journaled a pulley and to which shaft is attached a circular saw, a downwardly-projecting arm attached to or forming part of the free end of the horizontal arm and bifurcated at its lower or free end, a roller journaled in the bifurcated arm, a raised guide secured to the edge of the table upon which the roller in the bifurcated arm runs, a belt extending from the saw-carrying shaft to the shaft suspended from the ceiling, and means for revolving the said last-mentioned shaft and thereby the saw.
2. In a meat-sawing machine, the combination of the frame, a table mounted thereon, sliding platforms mounted on said table, clamping mechanism carried by the platforms at one end thereof, a support secured to the ceiling above the table, a swinging arm secured in said support, a right-angled arm swingingly secured at the lower end of said swinging arm, a revolute saw journaled in

the angle of the right-angled arm, a guide-roller journaled in the other end of said right-angled arm and adapted to slide on the top of the table, and pulleys journaled in the support, swinging arm, right-angled arm and to the saw and having belts adapted to rotate said pulleys and saw.

3. In a meat-sawing machine, the combination of a frame, a table mounted thereon, a support mounted on the ceiling above the table and carrying a shaft, driving mechanism mounted upon said shaft, a swinging arm suspended from said support on its shaft, a right-angled arm swingingly journaled at the lower end of said swinging arm, a circular saw journaled on a shaft at the angle of said right-angled arm, a handle secured on one face of the swinging arm, platforms sliding in grooves in the upper face of the table, a roller journaled in each platform and means for holding the meat on the roller, means for rotating the saw connected to said driving mechanism, and a guide-roller journaled at the lower end of the right-angled arm to guide the saw and hold it in a straight line.

4. In a meat-sawing machine, the combination of a frame, supporting a table carrying sliding platforms, a swinging arm suspended from above the table, a right-angled arm journaled on the shaft located in the lower end of the swinging arm, a shaft located in the angle of the right-angled arm, a pulley journaled upon said shaft and a circular saw also attached to the same shaft, platforms sliding in grooves in the upper face of the table, a roller journaled in each platform, and means for holding the meat on the roller also secured to the sliding platform, and means for revolving the saw to saw the meat.

In testimony whereof I affix my signature in presence of two witnesses.

DAVID LIPPY.
